Primary Examiner — Mark Goodwin(74) *Attorney, Agent, or Firm* — McNair Law Firm, P.A.(57) **CLAIM**

The ornamental design for a lawnmower, as shown and described.

DESCRIPTION

FIG. 1 is a perspective view of a lawnmower in accordance with an embodiment of the present invention;

FIG. 2 is a top view of the lawnmower of FIG. 1;

FIG. 3 is a bottom view of the lawnmower of FIG. 1;

FIG. 4 is a left side view of the lawnmower of FIG. 1;

FIG. 5 is a right side view of the lawnmower of FIG. 1;

FIG. 6 is a front view of the lawnmower of FIG. 1; and,

FIG. 7 is a rear view of the lawnmower of FIG. 1.

The broken lines of FIGS. 1-7 are illustrative of the visible environmental structure of the lawnmower and form no part of the claimed design.

1 Claim, 7 Drawing Sheets(56)
